UNITED STATES PATENT OFFICE.

PETER H. SAGER, OF MARIANNA, FLORIDA.

TOILET ATTACHMENT.

1,287,113.

Specification of Letters Patent. Patented Dec. 10, 1918.

Application filed February 7, 1918. Serial No. 215,868.

To all whom it may concern:

Be it known that I, PETER H. SAGER, a citizen of United States, residing at Marianna, in the county of Jackson and State of Florida, have invented certain new and useful Improvements in Toilet Attachments; and I do hereby declare the following to be a full, clear, and exact description of the invention, such as will enable others skilled in the art to which it appertains to make and use the same.

This invention relates to an attachment for toilets or water closets, and the primary object of the invention is to provide foot operated means for raising and lowering the cover or seat of the bowl and also for flushing the toilet.

More specifically, the object of this invention is to provide a longitudinally movable bar which is connected to the pivoted seat or cover of a toilet bowl and also to provide a plurality of pawls, and levers which are controlled by the depressions of foot rods for moving the bar longitudinally to move the pivoted seat and also to operate the flushing mechanism of the toilet at the time when the seat is started to be moved into a closed position.

With the foregoing and other objects in view this invention consists in such novel features of construction, combination and arrangement of parts as will be hereinafter more fully described, illustrated in the accompanying drawings and claimed.

In describing the invention in detail, reference will be had to the accompanying drawings wherein like characters designate like and corresponding parts throughout the several views and in which:

Figure 1 is a side elevation of a toilet showing the improved attachment applied thereto and showing the toilet being closed.

Fig. 2 is a view similar to Fig. 1 showing the toilet seat in a raised position.

Fig. 3 is a top plan of the toilet showing parts of the attachment in section.

Fig. 4 is a section on the line 4—4 of Fig. 2.

Fig. 5 is a section on the line 5—5 of Fig. 1.

Fig. 6 is a section on the line 6—6 of Fig. 1, and

Fig. 7 is a section on the line 7—7 of Fig. 1.

Referring more particularly to the drawings, 1 indicates an ordinary toilet bowl,

which has the usual type of pivoted cover 2 of the seat of the same. The toilet bowl 1 is supported on the floor 3, and a supporting plate or board 4 is attached to the under surface of the floor 3 and extends downwardly therefrom. The supporting board or plate 4 has a plurality of rollers 5 rotatably carried thereby which form guides for guiding the longitudinal movement of a bar 6. The bar 6 is connected by means of a pin 7 to the cover 2 of the toilet, so that the cover will be moved upon its hinges, upon longitudinal movement of the bar 6.

The plate 4 has a peculiarly shaped pawl 8 pivotally carried thereby as shown at 9, and this pawl is provided with a projecting point 10. The point 10 is provided with a notch 11, near its outer end, at one edge of the same and the upper side of the extension 75 terminates in an abrupt shoulder 12 which extends outwardly and communicates with the curved side 13 of the pawl.

The bar 6 has pins 14 and 15 carried thereby between which the extension 10 projects, as clearly shown in the drawings. A second pawl 17 is pivotally connected as shown at 18 to the supporting plate 4, and it has a spring 18 connected thereto which tends to hold the lower recessed end of the pawl 17 in an extended position toward the pawl 8, as shown in Fig. 1 of the drawings. A roller 19 is rotatably supported by the free end of the pawl 18.

When the toilet seat cover 2 is in a closed position, the bar 6 is in a downwardly projected position, and the pawl 8, is engaged by a lever 20 which is pivotally mounted intermediate its ends, as shown at 21. A spring 22 is connected to the lever 20 above its pivot 21 and to the supporting plate 4. When the bar 6 is in a downwardly extended position, the upper end of the lever 20 is engaged by the lower end of a foot lever or tread 23 which is slidably carried by the floor 3 and projects above the same, so that when it is desired to raise the cover 2, the foot lever 23 is depressed, which depression, together with the assistance of the spring 22 will move the normal upper end of the lever 20 downwardly, rocking the lever 20 and causing it to rock the pawl 8. The pawl 8, is, when the bar faces in a downwardly projected position engaged by the pin 14 so that when this pawl is rocked, by the rocking of the lever 20 it will be forced upwardly upon its pivot which will move the bar 6 upwardly,

causing it to raise the cover 2 into the position as indicated in Fig. 2 of the drawings, at which time the end of the extension 10 of the pawl is seated in the recess formed in the pawl 18. This pawl 18 supports the pawl 8 in its upper positions, for the period of time that the cover 2 is raised. To lower the cover 2, pressure is applied to a second foot lever 24 which is slidably carried by the floor 10 3 and engages the edge of the enlarged portion 13 of the pawl 8. When the foot lever 24 is depressed, it will rock the pawl 8 upon its pivot 9, moving it downwardly and moving the end of the extension pin out of the recess of the pawl 18, causing the lower edge of the extension to engage the pin 15, and move the bar 6 downwardly with the downward movement of the pawl. This downward movement of the pawl will also rock 20 the lever 20, causing it to resume its normal position and to force the foot lever 23 upwardly through the floor into a position to be operated. The rod or chain 25 which operates the flushing mechanism of the toilet 25 has a pin 26 carried thereby which pin is engaged by a pivoted pawl 27. The pawl 27 is pivotally secured to a suitable support 28 as at 27'. When the bar 6 is moved into its upper position by the depression of the foot 30 lever 23, the upper end of the bar will slide between the pivoted pawl 27 and when the foot lever 24 is depressed for lowering the cover 2, a slight upward and outward movement will be imparted to the upper end of the bar 6 which will rock the pawl 27. The rocking of the pawl 27 causes the same to engage the pin 26, thus forcing the rod or chain 25 downwardly, so that the toilet 1 will be flushed at the same time that the cover 40 2 is lowered.

In reducing the invention to practice, certain minor features of construction, combination and arrangement of parts may necessitate alterations to which the patentee is entitled provided such alterations are comprehended within the scope of what is claimed.

What is claimed is:

1. The combination with a toilet having a pivoted cover, of a bar connected to said cover, a pair of pins carried by said bar, a pivoted pawl, and a pair of foot levers for rocking said pawl to move said bar to raise or lower said cover.
2. The combination with a toilet having a hinged cover, and a flushing mechanism

therefor, of a longitudinally movable bar, a pair of pins carried by said bar, a pivoted pawl, foot levers for operating said pawl to strike said pins and move said bar longitudinally to raise or lower said cover, and means operated by said bar to operate said flushing means when said cover is lowered. 60

3. The combination with an article having a pivoted cover, of a bar connected to said cover, a pair of pins carried by said bar, a pivotally mounted pawl having a portion extending between said pins, a pivotally supported lever engaging one edge of said pawl, a foot lever engaging said last named lever 70 for moving said pawl upon depression of the foot lever to move said rod upwardly to move said cover into an open position.

4. The combination with an article having a pivoted cover, of a bar connected to 75 said cover, a pair of pins carried by said bar, a pivotally mounted pawl having a portion extending between said pins, a pivotally supported lever engaging one edge of said pawl, a foot lever engaging said last named lever 80 for moving said pawl upon depression of the foot lever to move said rod upwardly to move said cover into an open position, a second pivotally mounted pawl provided with a recess for receiving the end of said first named 85 pawl when the first named pawl is in an upper position.

5. The combination with an article having a pivoted cover, of a bar connected to said cover, a pair of pins carried by said bar, a 90 pivotally mounted pawl having a portion extending between said pins, a pivotally supported lever engaging one edge of said pawl, a foot lever engaging said last named lever for moving said pawl upon depression 95 of the foot lever to move said rod upwardly to move said cover into an open position, a second pivotally mounted pawl provided with a recess for receiving the end of said first named pawl when the first named pawl 100 is in an upper position, a second foot lever attached to engage said pawl when it is in an upper position whereby the pawl will be moved downwardly upon depression of the second foot lever to move said bar downwardly to close said cover.

In testimony whereof I affix my signature in presence of two witnesses.

PETER H. SAGER.
